(57) **CLAIM**

The ornamental design for a track shoe, as shown and described.

DESCRIPTION

FIG. 1 is a rear left perspective view of a track shoe showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof.

The dashed lines on the track shoe represent stitching and form a part of the claimed design. The broken lines showing portions of the track shoe bottom in FIGS. 2 and 7 form no part of the claimed design.
